UNITED STATES PATENT OFFICE.

WILLIAM F. DOYLE, OF REEDSBURG, WISCONSIN, ASSIGNOR OF ONE-HALF TO EDWARD G. STOLTE, OF REEDSBURG, WISCONSIN; FLORENCE P. STOLTE ADMINISTRATRIX OF SAID EDWARD G. STOLTE, DECEASED.

COOLING SYSTEM.

1,133,712.

Specification of Letters Patent. Patented Mar. 30, 1915.

Application filed October 8, 1913. Serial No. 794,139.

To all whom it may concern:

Be it known that I, WILLIAM F. DOYLE, a citizen of the United States, residing at Reedsburg, in the county of Sauk and State 5 of Wisconsin, have invented new and useful Improvements in Cooling Systems, of which the following is a full, clear, concise, and exact description, reference being had to the accompanying drawing, forming a part of 10 this specification.

My invention relates to cooling systems and particularly to systems for cooling the medium utilized in an internal combustion engine to cool the working parts thereof.

15 It is well known that as a liquid is volatilized heat is absorbed to such an extent that a considerable cooling effect is obtained.

It is one of the objects of my invention to provide means for utilizing this refrigerating effect to cool the water, air or other medium used in cooling the cylinders and working parts of an internal combustion engine.

It has been the ordinary practice, heretofore, to run the water from the jacket of the engine cylinder through a radiator whereby the water becomes somewhat cooled before returning to the jacket. In the case of engines running at high speed, however, or

30 where an engine driven vehicle travels over hilly, muddy or sandy roads, the engine becomes excessively heated and the water consequently becomes too hot to properly perform its cooling function, often reaching a 35 boiling point whereby serious injury may be caused to the engine and its working efficiency materially impaired, all of which is well known. My invention removes the possibility of such deleterious results by providing means for cooling the water or other medium to such an extent that it will always be at a proper temperature to carry out its necessary function.

It is a further object of my invention to 45 provide an apparatus for cooling the engine cooling medium that is simple in structure, economical to manufacture, easy to install, readily repaired and cleaned, and efficient in operation.

50 In the following description and accompanying drawings I have disclosed one preferred embodiment of my invention, it being understood that numerous changes may be made in the form, construction and arrange-

ment of the parts without departing from 55 the spirit of the invention or exceeding the scope of the appended claims.

In the drawings: Figure 1 is a view in elevation showing my invention attached to an ordinary internal combustion engine; 60 Fig. 2 is a vertical cross section of the device removed from the engine; Fig. 3 is a cross section, with parts broken away, taken on the line 3—3 of Fig. 2 looking in the direction of the arrows; Fig. 4 is a cross section 65 taken on the line 4—4 of Fig. 3, looking in the direction of the arrows, showing in detail the construction of one of the cells; Fig. 5 is a similar view taken on the line 5—5 of Fig. 2; Fig. 6 is a vertical cross sectional 70 view of a modified form of apparatus; Fig. 7 is a cross section taken on the line 7—7 or Fig. 6, looking in the direction of the arrows; Fig. 8 is a cross section taken on the line 8—8 of Fig. 6, showing in detail the 75 construction of one of the cells; Fig. 9 is a similar view taken on the line 9—9 of Fig. 6; Fig. 10 is an enlarged cross sectional view, the section being taken on the line 10—10 of Fig. 2, looking in the direction of the ar- 80 rows; and Fig. 11 is a view in elevation showing in detail one of the distributing plates.

Like reference characters refer to like parts throughout the following description 85 and the several figures of the drawings.

In the embodiment of my invention here shown as a preferred example, the intake manifold 10 of an ordinary internal combustion engine 11 is provided with an enlargement immediately above the carburetor 12, in the form of a casing 13 which is secured to the intake pipe 10 in any suitable manner as by the bolts and nuts 14. The casing 13 is provided with a cap 15 secured 90 thereto as at 16 and connected to the intake pipe 10 as at 16a. The casing 13 has a shoulder 17 on opposite sides of which are secured or formed integral therewith, bosses 18, externally screw-threaded to engage the 95 internally screw-threaded members 19 which latter serve as bearings for the pipes 20 and 20a leading from and to the cylinder jackets. Suitable packing is provided as shown at 21. Within the casing 13 are arranged a number 100 of parallel, long, narrow, thin walled cells 22, set close together. On each cell near the top is formed a pair of shoulders

23. The ends of the shoulders are open, the cell being otherwise completely closed. This is accomplished by forming the cell of a single piece of material bent backward 5 upon itself, thus closing the top, and by contracting the edges of the sides and bottoms of the walls and embracing the contracted portion by the clip like member 22^a.

Arranged across the shoulders 23 of the 10 cells 22, on either side of the apparatus, is a distributing plate 24 having openings 25 therein which correspond with the open ends of the cells 22. Secured to each distributing plate 24 by bolts 26 is a plate 24^a having 15 formed therein a bushing 24^b adapted to form connection with the pipes 20 and 20^a. Thus it will be seen that the water from the pipe 20 (taking water as an example of the engine cooling medium) is adapted to 20 pass through the cells 22, the structure of the distributing plates 24 preventing access to the interspaces. In order that the water will not merely cross the cells but will circulate thoroughly therethrough I provide a 25 baffle. To this end, the walls of the cells 22 are struck in, as shown at 27 (Fig. 4) to such an extent that the struck in portions approximately meet and thus substantially divide the cell down the middle thereof. 30 The struck in portions do not, however, extend entirely from top to bottom of the cells, the point of their termination being clearly shown in Fig. 2 at 27^a. Below this point the cell is open from end to end as shown 35 in Fig. 5. It will be seen, therefore, that, with this structure, as the water circulates under the force of the pump usually provided therefor, it will pass from the pipe 20 through the openings 25 into the cells 22 40 and because it cannot cross the cells owing to the baffle formed by the struck in portions it will necessarily flow downward to a point below the baffle, (i. e., to a point below 27^a, Fig. 2) where it can cross the cells, up the 45 other side and out through the openings 25 to the pipe 20^a, as shown by the arrows in Fig. 2. Thus there is a complete and thorough circulation throughout the entire apparatus, the advantage of which is herein- 50 after mentioned. In order to drain the water when desired, I provide a pet cock 28 which, passing through the casing, is screwed into a manifold connecting the several cells. 55 It will be noted that the cells 22 and plates 24 form a structural unit which may be removed bodily and as a whole from the casing if it is desired to clean or repair the apparatus. This is accomplished by unscrewing the nuts 16 and 16^a and removing the cap 10, and severing the connection with the pipes 20 and 20^a and with the pet-cock 28, whereupon the structure may be lifted bodily from the casing. 60 65 The operation of the device is as follows:

The hot water is circulated under force of the pump through the cylinder jackets, pipe 20, cells 22 and pipe 20^a as heretofore described. Gas from the carbureter is drawn upward through the intake pipe 10 70 in the usual manner, and, reaching the enlarged portion thereof formed by the casing 13, passes through the numerous interspaces between the cells 22 and out through the orifice in the cap 15 into the upper part of 75 the intake manifold 10. The gas, which has just been volatilized exercises the refrigerating effect before mentioned and the water, brought in close proximity therewith, is cooled thereby. Since the water flows down, 80 across and up the numerous cells between which the gas is passing this refrigerating or cooling process is extremely thorough and complete and the water accordingly returns to the cylinder jackets at a proper 85 temperature to carry out its function of cooling the engine. When the throttle is opened to attain higher speeds or to meet hilly, sandy or muddy road conditions, the 90 engine, and consequently the water, will become more and more heated. But inasmuch as, with the wider throttle, more gas is drawn through the intake manifold the refrigerating effect will be greater and so the 95 water is continuously returned to the jackets at a proper temperature.

It is to be understood that the apparatus may be used either with or without the usual radiator and is adapted for use with any engine cooling medium that is capable 100 of the necessary circulation, water being chosen merely as an example for the purposes of description.

In the modification illustrated in Figs. 6-9 inclusive, the structure is in general the 105 same except that the apparatus is so arranged that the gas from the carbureter passes through the cells and the water flows through the interspaces. The intake pipe 10 is provided with an enlarged portion as before in the form of a casing 40. Upper and lower caps 41 and 42 are secured to the casing by any suitable means as at 43 and 44 and to the intake pipe 10 as at 45 and 46, the caps 41 and 42 having openings therein corresponding to the pipe 10. The casing 40 has, on opposite sides thereof, shoulders 47 and 48 to which are secured or formed integral therewith, bushings 49 and 50 which engage the ends of the water pipes 20 and 20^a. Within the casing 40 are arranged a series of long, narrow, thin walled cells 51 set close together and parallel as before, but open at the top and bottom. These cells 51 are secured to top and bottom tube plates 52 and 53 so that the cells form a part of the continuity of the intake pipe 10 and the interspaces are closed therefrom. The top tube plate 52 extends beyond the cells 51 to overlap and be secured to shoulders 55 and 115 120 125 130 135

55^a on the casing 40 by the screws 54. Around the cells 51 at the bottom, its lower edge flush with the lower edge of the tube plate 53, is arranged a thin band 56 which 5 bears against packing 57, the casing being somewhat enlarged to provide accommodation therefor. As above mentioned the water pipes 20 and 20^a open into the casing 40 and the water is adapted to flow there- 10 through. In order to attain a thorough circulation and to prevent the water from merely passing across the interspaces I supply a baffle as before. The cell walls are struck outwardly (as shown at 58, Fig. 8) 15 to such an extent that the struck out portions of neighboring walls approximately touch and substantially close each inter- space against any horizontal passage of the water. The water, by necessity, flows down- 20 ward, therefore, to beyond the point 58^a where the walls are no longer struck out (the extent of the baffle being clearly shown in Fig. 6). It then crosses, passes up the other side and out via the pipe 20^a back to 25 the cylinder jackets. The circulation through the apparatus is thus substantially similar to that before described except that in the present structure the water flows through the interspaces instead of through 30 the cells. To drain the water when necessary I provide a pet-cock 59. The cells 51 and tube plates 52 and 53 form a structural unit as before, which may be bodily re- 35 moved from the casing for cleaning or re- pairs, it being only necessary to remove the cap 41 and the screws 54. The operation is substantially similar to that already de- 40 scribed except, as mentioned above, the gas passes upward through the cells and the water circulates through the interspaces as hereinbefore described.

Having thus described my invention, what I claim as new and desire to secure by Letters Patent, is:

45 1. In a cooling system, the combination with a casing, of a plurality of thin parallel plates located within the casing and parallel with the sides thereof and forming two sepa- 50 rate sets of passages, one set of passages having passed therethrough an engine cool- 55 ing medium, and the other set connected to the supply of newly volatilized combustible vapor for an internal combustion engine, so that the combustible vapor will absorb the heat of and re-cool the engine-cooling me- 60 dium.

65 2. In a cooling system, the combination with a casing, of a plurality of thin walled parallel cells therein and parallel to the sides thereof which together with the casing form two sets of passages, one set being connected with a supply of engine-cooling me- 70 dium, and the other set being connected with a supply of newly volatilized combustible vapor for an internal combustion en-

gine, so that the combustible vapor will absorb the heat of and re-cool the engine-cooling medium.

3. In a cooling system, the combination with a casing, of a plurality of thin walled cells therein, said cells and casing forming two separate sets of passages, one set of passages being connected with a supply of engine cooling medium, the other set being connected with a supply of newly volatilized combustible vapor for an internal combustion engine, and a baffle forming ribs in the side walls of said cells, said ribs extending into the passages connected with said engine cooling medium, to cause a thorough circulation of said engine-cooling medium through said passages, whereby said newly volatilized combustible vapor in passing through will absorb the heat of and re-cool said engine-cooling medium.

4. In a cooling system, the combination with an internal combustion engine and an intake pipe and carbureter associated therewith, of circulating conduits for an engine cooling medium, a casing interposed be- 90 tween said intake pipe and carbureter, and a plurality of thin plates located within said casing, said plates forming two sepa- 95 rate sets of passages, one set being connected with said circulating conduits for the passage of the engine cooling medium, the other set being connected with the intake pipe for the passage of the gases from the carbureter, for refrigerating said engine cooling medium.

5. In a cooling system, the combination with an internal combustion engine and an intake pipe and carbureter associated therewith, of circulating conduits for an engine cooling medium, a casing interposed be- 105 tween said intake pipe and carbureter, and a plurality of thin plates located within said casing, said plates forming two sepa- 110 rate sets of passages one set being connected with said circulating conduits for the pas- sage of the engine cooling medium, the other set being connected with the intake pipe for the passage of the gases from the carbureter, for refrigerating said engine cooling medium, said plates forming a unitary 115 structure removable bodily and as a whole from said casing.

6. In a cooling system, the combination with an internal combustion engine and an intake pipe and carbureter associated therewith, of circulating conduits for an engine cooling medium, a casing interposed be- 120 tween said intake pipe and carbureter, a plurality of thin plates located within said casing, said plates forming two separate 125 sets of passages, one set being connected with said circulating conduits for the pas- sage of the engine cooling medium, the other set being connected with the intake pipe for the passage of the gases from the carbure- 130

reter, and a baffle associated with said first named set of passages to insure thorough circulation of the engine cooling medium therethrough for refrigerating said engine cooling medium.

7. In a cooling system, the combination with an internal combustion engine and an intake pipe and carbureter associated therewith, of circulating conduits for an engine cooling medium, a casing interposed between said intake pipe and carbureter, and a plurality of thin plates located within said casing, said plates forming two separate sets of passages, one set being connected with said circulating conduits for the passage of the engine cooling medium, and the other set being connected with the intake pipe for the passage of the gases from the carbureter, said plates being struck in to form a baffle in said first named set of passages to insure thorough circulation of said engine cooling medium therethrough, for refrigerating said engine cooling medium.

8. In a cooling system, the combination with an internal combustion engine and an intake pipe and carbureter associated therewith, of circulating conduits for an engine cooling medium, a casing interposed between said intake pipe and carbureter, and a plurality of thin plates located within said casing, said plates forming two separate sets of passages, one set being connected with said circulating conduits for the

passage of the engine cooling medium, the other set, for the passage of the gases from the carbureter, opening directly into the intake pipe, for refrigerating said engine cooling medium.

9. In a cooling system, the combination with an internal combustion engine and an intake pipe and carbureter associated therewith, of circulating conduits for an engine cooling medium, a casing interposed between said intake pipe and carbureter, a plurality of thin plates located within said casing, said plates forming two separate sets of passages, one set being connected with said circulating conduits for the passage of the engine cooling medium, the other set being connected with the intake pipe for the passage of the gases from the carbureter, and a baffle associated with said first named set of passages to insure thorough circulation of said engine cooling medium through said passages, for refrigerating the engine cooling medium, said plates and said baffle forming a unitary structure removable bodily and as a whole from said casing.

In witness whereof, I have hereunto subscribed my name in the presence of two witnesses.

WILLIAM F. DOYLE.
